SHOESHINE STAND

Denis Miles Carter, Iver, England, assignor to Idealware,
Inc., Hollis, Long Island, N.Y., a corporation of New York

Filed Mar. 16, 1960, Ser. No. 59,779

Term of patent 14 years

(Cl. D9—2)

FIG. 1.

FIG. 2.

FIG. 3.

FIG. 5.

FIG. 4.

FIG. 6.

FIG. 6 is a sectional view thereof taken through the line 6—6 of FIG. 2, looking in the direction of the arrows.

I claim:

The ornamental design for a shoeshine stand, substantially as shown.
